Primary Examiner — Jeffrey D Asch

Assistant Examiner — Samantha N Wood

(57) **CLAIM**

The ornamental design for a shaver, as shown and described.

DESCRIPTION

The patent or application file contains at least one drawing executed in color. Copies of this patent or patent application publication with color drawing(s) will be provided by the Office upon request and payment of the necessary fee.

1. Shaver

1.1 is a front perspective view showing the shaver of my design;

1.2 is a left side elevational view thereof;

1.3 is a right side elevation view thereof;

1.4 is a front elevation view thereof;

1.5 is a rear elevation view thereof;

1.6 is a top plan view thereof; and

1.7 is a bottom plan view thereof.

1 Claim, 4 Drawing Sheets

The portion of the drawing shown in the color yellow is for the purpose of illustrating portions of the shaver and form no part of the claimed design.

(4 of 4 Drawing Sheet(s) Filed in Color)
